METHOD OF AND APPARATUS FOR SEPARATING AND ALIGNING JAR RINGS

Walter J. Baker, Somerville, Mass., assignor to Boston Woven Hose and Rubber Company, Cambridge, Mass., a corporation of Massachusetts

Application April 13, 1933. Serial No. 665,951.

7 Claims. (Cl. 214—1)

This invention relates to a method of and to apparatus for separating and aligning jar rings.

In the various machines for the counting and packaging of jar rings of which I am aware, considerable difficulty has been experienced in obtaining satisfactory operation of the counting mechanism. Unsatisfactory and inefficient operation of the counting mechanism in these machines has been caused by the jar rings sliding around the counting mandrel so that their lips are not aligned and also because the jar rings often become stuck together during manufacture, and the misaligning and sticking of the jar rings causes miscounting and jamming of the counting mechanism.

The object of the present invention is to provide a method of and apparatus for separating and aligning the jar rings, preferably after they have been placed on the counting mandrel, in order to secure more satisfactory and efficient operation of the counting mechanism than has heretofore been possible.

With this general object in view and such others as may hereinafter appear, the invention consists in the method of and apparatus for separating and aligning jar rings hereinafter described and particularly defined in the claims at the end of this specification.

In the drawings illustrating the preferred embodiment of the present invention, Fig. 1 is a plan view of the preferred apparatus; Fig. 2 is a sectional view taken on the line 2—2 of Fig. 1; and Fig. 3 is a sectional view taken on the line 3—3 of Fig. 1 omitting constructional details.

In general, the present invention contemplates a method of and also apparatus for aligning and preferably separating as well as aligning jar rings by subjecting the jar rings to rotation and preferably to both rotation and agitation, the rotation being used to bring the jar rings into alignment and the agitation to separate the individual jar rings from one another.

In the preferred form of apparatus embodying the present invention, the jar rings are placed on the counting mandrel in the usual manner, but before being placed in the counting machine provision is made for imparting rotation and agitation to the jar rings to cause them to become aligned and separated.

Referring now to the drawings wherein I have illustrated the preferred embodiment of the invention, 10 represents a mandrel which is adapted to be received in the counting machine after the process of aligning and separating the jar rings has been completed. The mandrel 10 is

supported on mandrel drive rolls 12, 13, 14 and 15, as herein illustrated, and is provided at one end with a suspension button 11 adapted to be received in a slot 16 in a frame 8 to prevent lateral movement of the mandrel. The suspension button 11 is also utilized to support the mandrel in the magazine of the counting machine. The mandrel drive rolls 12, 13 and 14, 15 are mounted on shafts 18 and 19, respectively. The shafts 18 and 19 are rotatably supported in suitable bearings 20 located in the frame 8, and are provided with gears 21, 22 which cooperate with gears 23, 24 located on a main driving shaft 25. The main driving shaft 25 is provided with a sheave 26 which may be connected by a belt 27 to any suitable source of power such as an electric motor (not shown).

In order to agitate the jar rings I have provided an agitator bar 28 which is slidably mounted in bearings 29 located in the frame 8. The agitator bar 28 is positioned so that it will be in contact with jar rings 30, as illustrated in Fig. 3, and reciprocating motion is imparted to the agitator bar 28 by a pinion 34 which cooperates with a rack 33 mounted on the lower side of the agitator bar. The pinion 34 is keyed to a shaft 38 which is rotated by a crank arm 40 connected by a crank 41 with a crank pin 42 located on a sprocket wheel 44. The sprocket wheel 44 is rotatably mounted on the frame 8 and is driven by a chain 45 from a sprocket wheel 47 on the main driving shaft 18. End stops 52, 54 are mounted in the frame, as illustrated in Fig. 2, so that the longitudinal travel of the jar rings is restricted to definite limits.

The operation of the mechanism is as follows:—When the mandrel 10 carrying the jar rings is placed on the mandrel drive rolls and the rolls rotated in a direction illustrated in Fig. 2, the mandrel is rotated by frictional contact with the mandrel drive rolls. The rotation of the mandrel 10 imparts rotary motion to the jar rings which are supported on it, causing them to be rotated until the lips 60 thereof come into contact with the agitator bar 28 which prevents further rotation of the jar rings and serves to effect alignment of the rings. The agitator bar is positioned as shown in Fig. 3 in contact with the jar rings and is reciprocated back and forth as herein described. The reciprocation of the agitator bar serves to agitate the jar rings and to cause separation of those jar rings which adhere to one another, so that the agitator bar serves as a combined means for aligning the jar rings and for separating the same.

From the description thus far, it will be observed that in accordance with the resent method and by the present apparatus, the jar rings may be aligned and separated from one another, in a simple, convenient and economical manner, and placed in a condition most suitable for subsequent operation in the counting mechanism.

While the preferred embodiment of the present invention has been herein illustrated and described, it will be understood that the invention may be embodied in other forms within the scope of the following claims.

Having thus described the invention, what is claimed is:

- 15 1. In a machine for aligning jar rings having lips, in combination, a supporting member for a plurality of the jar rings, means for imparting rotary movement to the supporting member to thereby impart rotary movement to the jar rings, and means positioned to engage the lips of the jar rings to arrest the rotary movement thereof and thereby effect alignment of the jar rings.
- 20 2. In a machine for separating and aligning jar rings having lips, in combination, supporting means for a plurality of the jar rings, means for imparting a rotary movement to the jar rings, means cooperating with the lips of the jar rings to arrest the rotary movement thereof and effect alignment of the rings, and means for moving the last mentioned means to effect separation of the rings from one another.
- 25 3. In a machine for aligning and separating jar rings having lips, in combination, a supporting mandrel for a plurality of the jar rings,

means for effecting rotation of the mandrel, and a reciprocatory abutment member positioned to cooperate with the lips of the rings to align the same and to effect agitation of the rings.

4. In a machine for aligning jar rings, in combination, means for supporting the jar rings, means for rotating said supporting means to impart rotary movement to the jar rings supported thereby, and means for arresting the movement of the jar rings while permitting continued rotation of the supporting means.

5. In a machine for separating and aligning jar rings, in combination, means for supporting the jar rings, means for rotating said supporting means, means for arresting the movement of the jar rings while permitting continued rotation of the supporting means, and means for agitating the jar rings.

6. In a machine for separating and aligning jar rings, in combination, a mandrel upon which the jar rings are mounted, means for rotating said mandrel, and means for agitating the jar rings supported on the mandrel.

7. The method of separating and aligning jar rings, which consists in assembling a plurality of the jar rings on a mandrel, rotating the mandrel to effect through frictional contact rotation of the jar rings, positioning an abutment in a position to be engaged by the lips of the rings as the latter are rotated to thereby cause alignment of the jar rings, and agitating the jar rings to cause their separation.
